United States Patent Office

Des. 187,880

Patented May 10, 1960

187,880

CHENILLE TEXTILE FABRIC OR SIMILAR ARTICLE

William Stark, New York, N.Y., assignor to Aileen Mills Company, Biscayne, N.C., a corporation of Delaware

Application October 5, 1959, Serial No. 57,810

Term of patent 14 years

(Cl. D92—1)

FIG. 1.

FIG. 2.

I claim:

The ornamental design for a chenille textile fabric or similar article, substantially as shown.
